UNITED STATES PATENT OFFICE

154,099

DESIGN FOR A TABLE LAMP

Vincent Cassara, New York, N. Y.

Application January 17, 1947, Serial No. 136,209

Term of patent 3½ years

(Cl. D48—20)

To all whom it may concern:

Be it known that I, Vincent Cassara, a citizen of the United States of America and resident of the city of New York, county of Kings, and State of New York, have invented a new, original, and ornamental Design for a Table Lamp, of which the following is a specification, reference being had to the accompanying drawing, forming part thereof.

Fig. 1 is a side elevation of a table lamp embodying my new design, and

Fig. 2 is a top plan view of the same.

I claim:

The ornamental design for a table lamp, substantially as shown.

VINCENT CASSARA.
